(57) **CLAIM**

The ornamental design for a truck LED light reflector, as shown and described.

DESCRIPTION

FIG. 1 is a front top perspective view of the truck LED light reflector of the present invention;

FIG. 2 is a top plan view thereof;

FIG. 3 is a bottom plan view thereof;

FIG. 4 is a front elevation view thereof, the rear view being identical; and,

FIG. 5 is a left side elevation view thereof, the right side elevation view being identical.

The broken lines shown in FIGS. 3, 4 and 5 illustrate mounting pegs and form no part of the claimed design.
